TELEPHONE AMPLIFIER

Harry M. Hamilton, 2024 Hardesty, Kansas City, Mo.

Filed Dec. 27, 1960, Ser. No. 63,334

Term of patent 7 years

(Cl. D26—14)

Fig. 1.

Fig. 4.

Fig. 3.

Fig. 2.

FIG. 1 is a perspective view of a telephone amplifier, showing my new design.

FIG. 2 is a top plan view thereof;

FIG. 3 is a side elevational view thereof; and

FIG. 4 is a rear elevational view of a telephone amplifier.

I claim:

The ornamental design for a telephone amplifier, as shown.
